CHILD'S CRIB

Nicholas Genovese, Brooklyn, N. Y.

Application June 29, 1949, Serial No. 3,634

Term of patent 14 years

(Cl. D5—5)

To all whom it may concern:

Be it known that I, Nicholas Genovese, a citizen of the United States, residing in the Borough of Brooklyn, county of Kings, city and State of New York, have invented a new, original, and ornamental Design for a Child's Crib, of which the following is a specification, reference being had to the accompanying drawing, forming a part hereof.

Fig. 1 is a top view of a child's crib, showing my new design.

Fig. 2 is a side view.

Fig. 3 is an end view.

I claim:

The ornamental design for a child's crib, as shown.

NICHOLAS GENOVESE.
